DESIGN FOR A CHAIR

Thomas E. Smith, New York, N. Y., assignor to
Swan Eng. Co., Inc., Newark, N. J., a corpora-
tion of New Jersey

Application September 19, 1939, Serial No. 87,283

Term of patent 7 years

To all whom it may concern:

Be it known that I, Thomas E. Smith, a citizen of the United States and a resident of New York, in the county of New York and State of New York, have invented a new, original, and ornamental Design for a Chair, of which the following is a specification, reference being had to the accompanying drawing, forming part thereof.

Figure 1 is a perspective view of a chair em-
bodying my new design.

Figure 2 is a front elevational view of the chair,
and

Figure 3 is a top plan view thereof.

I claim:

The ornamental design for a chair, as shown.
THOMAS E. SMITH.
